ROBERT H. STEVENS, OF LARCHMONT, NEW YORK

ELECTROMAGNETIC COIL

Application filed September 7, 1929. Serial No. 391,021.

The invention relates to electro-magnetic coils and has for its object to provide a coil of the indicated class which will operate automatically in response to variations in the intensity of light to which the coil is exposed. Other more specific objects will appear from the description hereinafter, and the features of novelty will be pointed out in the claims.

In the accompanying drawing, which shows an example of the invention without defining its limits, Fig. 1 is a perspective view of the novel coil; Fig. 2 is a longitudinal section thereof, and Fig. 3 is a diagrammatic view illustrating an installation for which the coil is particularly adapted.

As shown in the drawing, the novel electro-magnetic coil consists of the customary soft iron core 10, and the conventional insulated wire conductor 11 which is wound about said core 10 to form the conventional spool, as shown in Figs. 1 and 2. The novel coil further includes a cover 12 which encloses the conductor 11 and is made of any suitable insulating material, said cover 12 being fixed in place in any convenient way.

Upon its exterior the coil is provided with a conductor element, for instance selenium, the electrical conductivity of which varies in accordance with changes in light, and which is connected in series with the wire conductor 11, and is located in insulated relation thereto. In the illustrated example, the aforesaid conductor element extends exteriorly about the insulating cover 12 and consists of a second wire conductor 13 of selenium wound externally about said insulating cover 12 and connected in series with the first named wire conductor 11, as shown. The variable resistance element or wire conductor 13 in the illustrated example, thus comprises the outer layer of the electro-magnetic coil, and possesses the inherent characteristic of having its electrical conductivity responsive to changes in any light to which it may be exposed.

That is to say, in daylight or other light of corresponding or greater intensity, the conductor 13 when composed of selenium or its equivalent will develop an electrical resistance which increases as the intensity of the light to which it is exposed decreases,

so that in semi or complete darkness, said resistance will be at its highest point and thus, for instance, will bring about the closing of a suitable contact means whereby an electric current from a suitable source is permitted to freely pass over a predetermined circuit. As the darkness changes to light or the light increases in intensity beyond the point at which the conductor 13 is of increased resistance, its inherent characteristics will cause the resistance to be correspondingly decreased so that the aforesaid contact means is operated in a manner to arrest the passage of said electric current over said circuit. With the arrangement set forth electric current from the aforesaid suitable source may accordingly be cut off from the wire conductor 11 when the light to which the coil is exposed turns to darkness or its intensity is otherwise reduced, so that the core 10 may be de-magnetized during periods of darkness or semi-darkness. On the other hand when the light to which the coil is exposed is sufficiently intense the resistance developed in the wire conductor 13 will be reduced sufficiently to permit the core 10 to be magnetized and remain magnetically active during periods of light.

The novel light-sensitive coil may be used in a variety of ways for automatic control in accordance with light variations, and because of its compactness is easily installed in spaces of small dimensions. In all installations the coil is efficient and reliable and does away with the necessity for a plurality of separate units which heretofore have been found necessary in light sensitive controlling systems.

The novel coil is particularly adapted for automatically controlling the circuits of electric lights in a manner to switch on such lights automatically when a condition of darkness or semi-darkness is reached in the vicinity of the coil, and to switch off such lights when the darkness changes to light. As shown diagrammatically in Fig. 3 the coil may accordingly be efficiently used for automatically switching on the parking lights of an automobile when the latter re-

mains parked at a given place from daylight to darkness.

When thus used the parking lights, as represented by the incandescent bulb 14, may 5 be located in an electric circuit in which a wire 15 extends from one terminal of the lamp to an armature lever 16 pivoted in operative relation to the end of the core 10; in such case a second wire 17 extends from 10 the other terminal of the lamp 14 to a suitable switch 18 which in turn is connected by means of a wire 19 with one pole of a conventional battery 20 or other source of electricity. The opposite pole of said battery 15 20 or its equivalent is connected by means of a wire 21 with a contact 22 which operates with a contact 23 carried by the armature lever 16 to control the circuit in which the lamp 14 is located; for purposes 25 of adjustment the contact 23 may consist of a screw mounted in threaded engagement with said lever 16.

In addition to the above the wire conductor 11 of the electro-magnetic coil is connected with one pole of the battery 20 for instance by means of a wire 24 cut in on the wire 17 at a point between the switch 18 and the lamp 14. The light sensitive wire conductor 13 or its equivalent is, in turn, 30 connected with the other pole of said battery 20 for instance, by means of a wire 25 cut in on the wire 21 to complete the circuit. It will of course be understood that the circuit may be otherwise arranged to produce 35 the same or equivalent results.

A coil spring 26 may be provided for returning the armature lever 16 to the position in which, in Fig. 3 of the illustrated example, the contacts 22 and 23 are in engagement 40 with each other. In addition the customary adjustable stop 27 may be provided for arresting the movement of the armature lever 16 by the action of the spring 26; in the form shown in the drawing the stop 27 consists 45 of a suitable screw mounted in a stationary support 28 as shown in Fig. 3.

In practice where an automobile equipped with the novel control means is parked at a time of the day when darkness approaches, 50 and it is desired to have the parking light or lights automatically switched on at the proper time, the switch 18 is closed to bring the battery 20 into closed circuit with the lamp 14 and the novel control coil.

55 As long as sufficient daylight remains in the vicinity of the parked automobile, the light effective upon the conductor 13 will decrease the resistance therein sufficiently to permit the passage of the current from the battery 20 to the coil conductor 11. The core 60 10 accordingly is brought to a magnetized condition and the armature lever 16 is attracted by the core 10 and the contacts 22 and 23 are separated so that the light circuit 65 is broken. When a condition of darkness

is reached the resistance in the conductor 13 will be gradually increased to a point at which obstruction to passage of the battery current to the coil conductor 11 is developed, so that the core 10 gradually loses its magnetism and the tension of the spring 26 is finally sufficient to move the armature lever 16 away from the said core 10. As soon as this occurs the contact 23 will be brought into engagement with the contact 22 to close the lamp circuit, so that current will pass from the battery 20 to the lamp 14 to electrically energize the same. The entire system may be thrown out of operation at will 70 by simply opening the switch 18 which, in practice, will be located within easy reach of the chauffeur or other operator of the vehicle. Obviously if the latter is permitted to remain parked until darkness changes to daylight and the switch 18 remains in its closed position, the daylight, as soon as it reaches the required intensity, will again decrease the resistance in the conductor 13 whereby the 75 passage of the current from the battery 20 to the conductor 11 will again be permitted. At this point the core will be again magnetized and the armature lever 16 will be attracted by the core 10 and move the contact 23 away from the contact 22 and thereby 80 break the circuit in which the lamp 14 is located; as a result the lamp will be extinguished. 85

90 From the above it will be clear that the parking lights of an automobile, or the electric lights of any other system, may be automatically switched on and off in exact accordance with existing or developed conditions of light and darkness without the assistance or supervision of any human agency 95 other than the operation of closing the switch 18 if it forms a part of the installation. The novel device may be used with equal efficiency 100 for the corresponding control of other devices, and it is accordingly to be understood that the diagrammatic illustration of Fig. 3 is only an example of its utility. 105

110 In any case the device is reliable in its operation and control and because of its compactness may be embodied in an automobile 115 or other desired unit or in any place in an inconspicuous manner and without affecting the appearance or general operation thereof.

120 Various changes in the specific form shown and described may be made within the scope 120 of the claims without departing from the spirit of the invention.

I claim:—

1. An electro-magnetic coil comprising a core, a wire conductor arranged about said core, and a conductor element, the electrical conductivity of which varies in accordance with changes in light to which said coil is exposed, said conductor element being located externally about and in insulated con- 125

volute relation to said wire conductor and in series therewith.

2. An electro-magnetic coil comprising a core, a wire conductor of fixed electrical conductivity arranged about said core, a cover of insulating material enclosing said wire conductor, and a conductor strand, the electrical conductivity of which varies in accordance with changes in light to which said 10 coil is exposed, extending exteriorly about said insulating cover and connected in series with said wire conductor.

3. An electro-magnetic coil comprising a core, a wire conductor of fixed electrical conductivity arranged about said core, a cover of insulating material enclosing said wire conductor, and a second wire conductor, the electrical conductivity of which varies in accordance with changes in light to which 15 said coil is exposed, wound externally about said insulating cover and connected in series with said first named conductor.

4. A light-sensitive control system comprising an element to be controlled, an electric controlling circuit for controlling said element, a switching means in said circuit, an electro-magnetic coil arranged to operate said switching means, and light sensitive means carried by said coil in external convolute relation thereto and connected in series 20 with said coil whereby said electro-magnetic coil is energized in accordance with variations in light to which said coil is exposed.

5. A light-sensitive control system comprising an electric lamp, an electric circuit for supplying current to said lamp, contacts constituting terminals in said circuit, an armature lever carrying one of said contacts, an electro-magnet co-operating with said 35 armature lever to control said circuit, and a wire conductor, the electrical conductivity of which varies in accordance with changes in light, externally surrounding said coil in insulated relation thereto and connected in series with said coil, whereby said electro-magnet is energized in accordance with variations in the light to which said coil is exposed.

50 In testimony whereof I have hereunto set my hand.

ROBERT H. STEVENS.
